UNITED STATES PATENT OFFICE

PIERRE SALVAT, OF SAN FRANCISCO, CALIFORNIA

WOOD WORKING MACHINE

Application filed April 14, 1930. Serial No. 444,051.

My invention relates to improvements in wood working machines wherein a motor, provided with a shaft arranged to receive any of a plurality of cutters of various form, is arranged to be adjusted vertically and also pivotally about an axis at right angles to the axis of the motor shaft whereby the cutter may be shifted to numerous positions for operation in various manners and for various purposes.

The primary object of my invention is to provide an improved wood working machine.

Another object is to provide an improved wood working machine adjustable for operation in various manners and for various purposes.

A further object is to provide an improved machine of the character described having improved adjusting means affording a wide range and variety of adjustments and which facilitates the adjustment of the machine for various types of work.

Another object is to provide an improved machine of the character described provided with improved guide means for supporting and guiding materials presented to the cutter.

A still further object is to provide an improved wood working machine of simple, rugged, and efficient construction and which is simple and efficient in operation.

I accomplish these and other objects by means of the improved device disclosed in the drawings forming a part of the present application wherein like characters of reference are used to designate similar parts throughout the specification and drawings, and in which,

Fig. 1 is a broken plan view of my improved wood working machine, the table being removed and indicated in dotted lines;

Fig. 2 is a broken vertical transverse section of the machine;

Fig. 3 is a broken plan view of the machine with the table in operative position;

Fig. 4 is a broken sectional detail, drawn upon a larger scale, showing the manner in which a cutter is mounted upon the motor shaft;

Fig. 5 is a plan view of the guide as

mounted in connection with the motor and motor shaft;

Fig. 6 is a plan view of one form of an end cutter mounted upon the shaft;

Fig. 7 is a vertical section of the cutter shown in Fig. 6;

Fig. 8 is a section taken upon the line 8—8 of Fig. 2 in the direction indicated and showing means for adjusting the pillar about its axis; and

Fig. 9 is a broken plan view of the mounting sleeve end of the motor bracket.

Referring to the drawings, the numeral 1 is used to designate a base having a vertically disposed portion 2 recessed to receive the lower end of a pillar 3 rotatably mounted therein and extending vertically upward therefrom. The pillar 3 is hollow and has a slot 4 formed in one side thereof. A top plate 6 is secured upon the top of the pillar 3, said plate being disposed in a horizontal plane and being slotted as at 7 to match with the slot 4 of the pillar. A collar 8 is secured upon the pillar 3 to seat upon the upper end of the base portion 2, said collar being provided with a laterally extending handle 9 extending across a sector flange 11 upon the top of the base portion 2. A suitable securing member 12 carried by the handle 9 engages an arcuate slot 13 formed in the sector flange 11 whereby the pillar may be turned and secured in a desired position.

A bracket 16 is slidably mounted upon the pillar 3. The bracket 16 is provided with a bearing sleeve portion 17 engaging the pillar and having a tongue 18 extending into the pillar through the slot 4. The inner edge of the tongue 18 is provided with threads 19 cut therein to engage a threaded shaft 21 rotatably mounted within the pillar 3, said shaft 21 being arranged to be rotated in any convenient manner, as by a crank, not shown, inserted into a squared socket 22 formed in the upper end of the shaft, to raise or lower the bracket vertically relative to the pillar. The bracket 16 extends laterally from the pillar 3 upon the forward side thereof, and is bifurcated at its outer end to form arms 23 forming bear-

ings for the ends of a motor mounting shaft 24 extending between the arms in a horizontal plane.

A suitable electric motor 26 is mounted 5 between the arms 23 of the bracket 16 and supported upon the mounting shaft 24. The motor 26 is provided with a motor shaft 27 disposed at substantially right angles to the axis of the mounting shaft 23. One 10 end of the shaft 27 is extended axially outwardly and provided with a slot 28 to detachably engage a suitable cutting tool 29 of any desired form. The end of the shaft 27 is provided with a tapped aperture 31 to 15 receive a securing member 32 for securing the cutting tool 29 within the slot. The member 32 is also operative for securing a cutter 29' upon the end of the shaft, as shown in Figs. 6 and 7, as desired.

20 A sector worm gear 33 is secured in any convenient manner upon the motor concentric to the mounting shaft 24. A worm 34 is mounted upon a shaft 36 rotatably supported upon the bracket 16, said worm 34 25 meshing with the sector 33. The shaft 36 is provided with a suitable crank 37 or other suitable turning means whereby the worm may be rotated to actuate the sector and motor to desired adjusted positions.

30 A guide bracket 38 is adjustably and detachably mounted in connection with the motor, said bracket preferably comprising a collar fitted onto a shoulder 39 upon the motor, a set screw 40 being provided for 35 securing the collar in a desired position upon the shoulder. The guide bracket 38 is provided with an arm portion 41 bifurcated at its outer end to slidably receive a guide member 42 adjustably secured upon 40 the arm by means of a suitable clamping member 43. The clamping member 43 is adjustable along slots 44 formed in the bifurcations of the arm 41, and the guide 42 is provided with a longitudinal slot 46 where- 45 by the guide member may be adjusted longitudinally and pivotally upon the securing member.

50 A table 47 is pivotally connected to the top plate 6, preferably upon the rearward side of the machine, by means of a suitable hinge mounting 48. The table normally rests in a horizontal position supported by the top plate 6, and is arranged to be swung rearwardly to an inoperative position tilted 55 approximately 15° from the vertical. The table is provided with an opening 49 immediately over the motor 26 to permit the shaft 27 thereof to extend upwardly through the table. A plurality of nesting bushings 60 51 are provided to seat within the opening 49 upon a shoulder 52, the ends of said bushings 51 being arranged to lie flush with the surface of the table whereby the opening 49 may be closed except for the space necessary 65 to admit the shaft 27 through the table to

operate a cutter above the plane of the table, as shown in Figs. 2 or 4 of the drawings.

The motor 26 is connected to any suitable source of electrical energy and is controlled 70 by suitable circuit control means, not illustrated.

In operation, the motor 26 is normally adjusted to a position such as shown in full lines in Fig. 2 of the drawings, with the 75 motor shaft 27 extending vertically upward. A cutter 29 of desired form is secured upon the shaft 27, as shown in Figs. 4, 6, or 7. In doing flat work, the table 47 is lowered to its operative position, as shown in Fig. 2, 80 the shaft 26 extending upwardly through the opening 49 so that the cutter is supported and operated above the plane of the table. Material to be shaped is then supported upon the table, and moved past the 85 cutter in the desired manner.

For cutting irregular material, the table top 47 may be tilted rearwardly to an inoperative position, as indicated in dotted lines in Fig. 2. The shaft 27 is thus left exposed and the cutter is rendered accessible for cutting materials of irregular shape such as cannot be manipulated or cut in the desired form when supported upon the table. The guide member 42 is adjusted to a desired 90 position relative to the cutter 29 whereby the material may be supported in a desired relation to the cutter as said material is moved past the cutter.

95 For many kinds of work, it is desirable 100 to have the cutter downwardly disposed so that the work may be presented to the cutter from below or the cutter moved downwardly upon material supported below the bracket. For such purposes, the worm 34 is turned to 105 rotate the sector 33 and motor 26 about the axis of the mounting shaft 24, to the downwardly disposed position indicated in dotted lines in Fig. 2. Any temporary supporting surface may be placed below the cutter to 110 support materials to be cut, if desired, and the guide member 42 is carried with the motor so that said guide member may be adjusted to a desired position relative to the cutter in its downwardly disposed position. 115

120 In many cases it is desirable to have the motor shaft inclined at various angular positions between its extreme vertical position. The worm 34 may be turned to adjust the motor to any desired position between the extreme upwardly and downwardly disposed positions mentioned, and said worm serves to effectually lock the motor in any desired adjusted position. In Fig. 2 of the drawings, I have illustrated, in dotted lines, the manner in which the shaft 27 may be arranged to extend laterally outward in a horizontal position to receive a saw or other desired cutting member. The guide member 42, being normally carried with the 125 130

motor may be adjusted as desired, or if the guide is unnecessary for any particular work, the guide may be entirely removed.

5 The motor and cutter may be raised or lowered to desired positions by an appropriate turning of the threaded shaft 21 so that the cutter may be adjusted and held at any desired vertical position, or the cutter may be raised or lowered past work held in a fixed position. The pillar 3 may be turned upon its axis by means of the handle 9 for adjusting the cutter to a desired position, or for moving the cutter past material held rigidly in a fixed position.

15 While I have illustrated and described what I now regard as the preferred embodiment of my invention, the device is, of course, subject to modification in numerous ways without departing from the spirit of 20 my invention. I therefore do not wish to restrict myself to the specific details illustrated and described, but desire to avail myself of all modifications which may fall within the scope of the appended claims.

25 Having thus described my invention, what I claim as new and desire to secure by Letters Patent is—

1. A wood working machine comprising a supporting pillar; a bracket adjustably 30 mounted upon the pillar; a motor adjustably mounted upon the bracket and provided with a cutter shaft to receive a cutter of desired form; and a guide adjustably mounted adjacent the motor to guide materials moved past the cutter, said guide being movable with the motor to various adjusted positions thereof.

2. A wood working machine comprising a supporting pillar; a bracket adjustably 40 mounted upon the pillar; a motor adjustably mounted upon the bracket and provided with a cutter shaft to receive a cutter of desired form; a guide adjustably mounted adjacent the motor and movable with said 45 motor to various adjusted positions thereof to guide materials moved past the cutter; and a table mounted upon the pillar and movable from a normal operative horizontal 50 position adjacent the cutter to a rearwardly tipped inoperative position.

3. A wood working machine comprising a supporting pillar; a bracket slidably mounted upon the pillar said bracket being bifurcated at its outer end to form a pair 55 of yoke arms; means for adjusting the bracket vertically along the pillar; a motor mounting shaft journaled in the ends of the yoke arms a motor mounted upon the mounting shaft and provided with a motor 60 shaft extending axially therefrom to receive a cutter; and means for adjusting the motor about an axis transverse to the axis of the motor.

4. A wood working machine comprising 65 a supporting pillar; a bracket slidably

mounted upon the pillar; means for adjusting the bracket vertically along the pillar; a motor mounted upon the bracket and provided with a shaft extending axially therefrom to receive a cutter; means for adjusting the motor about an axis transverse to the axis of the motor; and a guide mounted adjacent the motor and cutter and movable with the same to adjusted positions thereof, and being adjustable relative to the motor and cutter.

5. A wood working machine comprising a supporting pillar; a bracket slidably mounted upon the pillar; means for adjusting the bracket vertically along the pillar; a motor mounted upon the bracket and provided with a shaft extending axially therefrom to receive a cutter; means for adjusting the motor about an axis transverse to the axis of the motor; a guide mounted adjacent the motor and cutter and movable with the same to adjusted positions thereof, and being adjustable relative to the motor and cutter; and a table pivotally mounted upon the top of the pillar and movable from a normal horizontal operative position adjacent to the cutter to a rearwardly tipped inoperative position.

6. A wood working machine comprising a supporting pillar; a bracket slidably mounted upon the pillar; means for adjusting the bracket vertically along the pillar; a motor mounted upon the bracket and provided with a shaft extending axially therefrom to receive a cutter; means for adjusting the motor about an axis transverse to the axis of the motor; a guide mounted adjacent the motor and cutter and movable with the same to adjusted positions thereof, and being adjustable relative to the motor and cutter; a table pivotally mounted upon the top of the pillar and movable from a normal horizontal operative position adjacent the cutter to a rearwardly tipped inoperative position; and means for adjusting the pillar and mechanism mounted thereon angularly about the axis of said pillar.

7. A woodworking machine comprising a supporting pillar; a bracket slidably mounted upon the pillar; means for adjusting the bracket vertically along the pillar; a motor pivotally mounted upon a horizontal axis transverse to the axis of the motor, said motor being provided with a shaft having an extension provided with means thereon to detachably engage a cutter; a worm mounted adjacent the motor; and a worm gear mounted upon the motor concentric with the horizontal mounting axis and engaged by the worm for adjusting the motor about its horizontal mounting axis to vary the position of the motor shaft.

8. A wood working machine comprising a supporting pillar; a bracket slidably mounted upon the pillar; means for adjust-

ing the bracket vertically along the pillar; a motor pivotally mounted upon a horizontal axis transverse to the axis of the motor, said motor being provided with a shaft having an extension provided with means thereon to detachably engage a cutter; a worm mounted adjacent the motor; a worm gear engaged by the worm and connected to the motor for adjusting the motor about its horizontal mounting axis to vary the position of the motor shaft; a guide bracket carried by the motor and movable therewith to various adjusted positions; and a guide adjustably mounted upon the bracket to guide materials moved past the cutter.

9. A wood working machine comprising a supporting pillar; a bracket slidably mounted upon the pillar; means for adjusting the bracket vertically along the pillar; a motor pivotally mounted upon a horizontal axis transverse to the axis of the motor, said motor being provided with a shaft having an extension provided with means thereon to detachably engage a cutter; a worm mounted adjacent the motor; a worm gear engaged by the worm and connected to the motor for adjusting the motor about its horizontal mounting axis to vary the position of the motor shaft; a guide bracket carried by the motor and movable therewith to various adjusted positions; and a guide adjustably mounted upon the bracket to guide materials moved past the cutter; and a table pivotally mounted upon the top of the pillar and having an opening to receive the cutter, said table being movable from a normal horizontal operative position to a rearwardly tipped inoperative position.

40 10. In a wood working machine, a motor provided with a shaft extending axially from one end of the motor and having means for detachably engaging a cutter; a mounting shaft carried by the motor for mounting the motor for rotative adjustment about a horizontal axis at right angles to the axis of the motor and shaft; and worm and gear means for adjusting the motor about its horizontal mounting axis to vary the position of the motor and cutter shaft between upwardly and downwardly extending vertical positions.

11. In a wood working machine, a motor provided with a shaft extending axially from one end of the motor and having means for detachably engaging a cutter; means for mounting the motor for rotative adjustment about a horizontal axis at right angles to the axis of the motor and shaft; means for adjusting the motor about its horizontal mounting axis to vary the position of the motor and cutter shaft between upwardly and downwardly extending vertical positions; a guide bracket mounted in connection with the motor and movable

therewith; and a guide adjustably mounted upon the guide bracket for adjustment relative to the cutter to guide materials moved past said cutter.

In witness whereof, I hereunto set my 70
signature.
